UNITED STATES PATENT OFFICE.

MAX S. ERSLER, OF CHICAGO, ILLINOIS.

LOOSE-LEAF BINDER.

1,050,440.

Specification of Letters Patent. Patented Jan. 14, 1913.

Application filed July 24, 1912. Serial No. 711,229.

To all whom it may concern:

Be it known that I, MAX S. ERSLER, a citizen of the United States, residing at Chicago, in the county of Cook and State 5 of Illinois, have invented a new and useful Improvement in Loose-Leaf Binders, of which the following is a specification.

My invention relates to improvements in loose-leaf binders for binding together sheets 10 of paper, cardboard, photographs, or the like, in a cabinet, box or the like, or in book-form; and my object is to provide a construction of binder which shall be of simple construction, may be economically 15 manufactured, and will cause the sheets to extend in compacted condition and when bound together in book-form to lie flat.

Referring to the accompanying drawings wherein my invention is illustrated as embodied in a loose-leaf binder of book-form: Figure 1 is a view in elevation, partly sectional, and in the nature of a diagram, of a loose-leaf binder of book-form constructed in accordance with my invention. Fig. 2 is 20 a perspective view of one of the two plate-members of my improved binder-device. Fig. 3 is a similar view of the other, lug-equipped member thereof. Fig. 4 is a broken perspective view of a portion of the 25 binder showing the manner of attaching it to a stiffening member for assembling with the cover-sections of a book; and Fig. 5, an enlarged section taken at the line 5 on Fig. 1 and viewed in the direction of the arrow. 30 The binder illustrated in the drawings and constituting the preferred embodiment of my invention, is formed of a pair of substantially flatwise opposed plates 6 and 7, the plate 6 being provided along its opposite edges with lugs 8 spaced apart as represented and bent to overlap the rear side of the plate 7, as represented in Fig. 5, for securing these plates together.

Straddling the plate 6 and extending between the latter and the plate 7 and through the spaces between the lugs 8, is a series of substantially parallel U-shaped links 9, the lugs 8 serving to pivotally confine the links in spaced relation on said plates. The links 45 50 9, which are in effect connected with said plates by hinge-joints, carry at their free ends, the clips, represented at 10, for engaging with and holding the sheets to be bound, one of which is indicated at 11. The 55 clips 10 may be of any desirable construction, those illustrated being constructed of

spring wire and comprising side-sections 12 connected together by cross-bars 13 and intersecting spring-sections 14 on the ends of said side-sections. The free ends of the 60 links 9 are formed into eyes 15 which surround the cross-bars 13 at the ends of the latter, and thus serve to hingedly connect the links and clips together, the bars 13 at the portions thereof surrounded by the eyes 65 15 being deflected, as represented at 16, to form seats for the eyes and thus prevent the links and clips from becoming disarranged.

The parts described and assembled as stated may be secured in any desirable manner in operative position in a cabinet, box or the like, or in cover-sections of a book. In the preferred construction illustrated, for assembling with the covers of a book, the back of the book and its front and back covers hinged thereto, being represented at 17, 18 and 19 respectively, the plate 7 is formed intermediate its marginal edges with tongues 20 cut from the metal of the plate and bent back at right angles thereto. The tongues 25 30 35 40 45 50 55 60 65 70 75 80 85 90 95 serve as the means for securing the plates 6 and 7 and the links 9 and clips 10 in the above-stated assembled relation, to a stiff plate-member 21, of wood or any other suitable material, which is preferably provided with a strip of fabric 22 at which the binder-device is adapted to be secured to the back 17 of the book between the book-covers 18 and 19, as by gluing the strip 22 at its free ends to the inner surfaces of the book-sections, as illustrated in Fig. 1. The tongues 20, to thus serve their purpose, extend through openings 23 in the member 21, and are clenched at their protruding ends against the rear surface of the member 21, as represented in Fig. 4.

In assembling the plates 6 and 7, links 9 and clips 10, the links 9 are applied to the plate 6, on which the lugs 8 extend at angles thereto, as represented in Fig. 3, to cause the links to extend cross-wise of the plate 6 at its rear side and into the spaces between adjacent lugs 8. The plate 7 is then seated upon the links 9 and between the two series of lugs 8 (Fig. 5), and the latter 100 105 then bent inwardly against the rear side of the plate 7 to firmly clamp the plates and links together.

It will be understood that by providing the double-hinge connection of the sheets 11 110 with the plates 6 and 7, the sheets and clips will lie flatwise in compact condition re-

卷之三

gardless of the place at which the book is opened.

What I claim as new and desire to secure by Letters Patent is—

5 1. In a loose-leaf binder, the combination
of a member, a series of U-shaped links
straddling said member and pivotally con-
nected therewith in substantially parallel,
and in spaced, relation, and clips, for hold-
10 ing the sheets, pivotally connected with the
ends of said links.

2. In a loose-leaf binder, a clip for holding the sheet, formed with a cross-bar, and a link having spaced arms terminating in eyes 15 surrounding said cross-bar at which said link and clip are pivotally connected together, said cross-bar being offset toward its opposite ends to form seats for said eyes, for the purpose set forth.

20 3. In a loose-leaf binder; a clip for holding the sheet, formed with a cross-bar, and a U-shaped link, the free ends of which terminate in eyes surrounding said cross-bar and at which said link and clip are pivotally connected together, said cross-bar being offset toward its opposite ends to form seats for said eyes, for the purpose set forth.

25

4. In a loose-leaf binder, the combination of a pair of flatwise-opposed plates secured together in spaced relation, spacers extending transversely of said plates, links, each pivoted at one end between said plates, alternating with said spacers, and clips, for holding the sheets, pivotally connected with said links.

5. In a loose-leaf binder, the combination of a pair of flatwise-opposed plates, one of which is formed along its opposite edges with lugs spaced apart and overlapping the other of said plates, links each extending at one end between said plates, said links alternating with said lugs and extending through the spaces between the latter to pivotally confine said links on said plates, and clips 45 for the sheets, pivotally connected with said links.

6. In a loose-leaf binder, the combination of a pair of flatwise-opposed plates, one of which is formed along its opposite edges with lugs spaced apart and overlapping the other of said plates, U-shaped links interposed between said plates and straddling said lug-equipped plate, said links alternating with said lugs and extending through the spaces between the latter to pivotally confine said links on said plates, and clips, for the sheets, pivotally connected with the free ends of said links, for the purpose set forth.

60 7. In a loose-leaf binder, the combination

of a pair of flatwise-opposed plates, one of which is formed along its opposite edges with lugs spaced apart and overlapping the other of said plates, said last-referred-to plate being provided with attaching tongues, 65 U-shaped links interposed between said plates and straddling said lug-equipped plate, said links alternating with said lugs and extending through the spaces between the latter to pivotally confine said links on 70 said plates, and clips, for the sheets, pivotally connected with the free ends of said links, for the purpose set forth.

3. In a loose-leaf binder, the combination of a relatively stiff member provided with a strip of relatively flexible material at which said member is adapted to be secured within the covers of a book, a series of links arranged in substantially parallel relation and pivotally connected with said member, and 80 clips, for the sheets, pivotally connected with said links, for the purpose set forth. 75

9. In a loose-leaf binder, the combination of a member, links confined on and movable relative to said member, and clips, for holding the sheets, pivotally connected with said links, said clips being formed of cross-bars at which they are pivotally connected with said links and with laterally-extending arms having sheet-gripping sections extending at 90 angles thereto and toward each other, said clips at their points of connection with said links being wider than the latter.

10. In a loose-leaf binder, the combination of a member, U-shaped links confined on and movable relative to said member, and clips, for holding the sheets, formed of cross-bars pivotally connected with the spaced arms of said links, and arms extending laterally of said cross-bars and spaced apart a greater distance than the width of said links and provided with sheet-gripping sections extending at angles thereto and toward each other. 105

11. In a loose-leaf binder, the combination 105
of a member, U-shaped links confined on and
movable relative to said member, and clips,
for holding the sheets, formed of cross-bars
pivotally connected with the spaced arms of
said links, and substantially parallel arms 110
extending laterally of said cross-bars, said
arms being spaced apart a greater distance
than the width of said links and provided at
their extremities with sheet-gripping sec- 115
tions extending at angles thereto and to-
ward each other. 116
